UNITED STATES PATENT OFFICE.

THOMAS H. WILLIAMS, OF JERSEY CITY, NEW JERSEY, AND EDWARD AMBROSE, OF TROY, NEW YORK, ASSIGNORS TO THE A. A. GRIFFING IRON COMPANY, OF JERSEY CITY, NEW JERSEY.

DESIGN FOR A RADIATOR.

SPECIFICATION forming part of Design No. 22,787, dated September 12, 1893.

Application filed August 7, 1893. Serial No. 482,616. Term of patent 7 years.

To all whom it may concern:

Be it known that we, THOMAS HILTON WILLIAMS, a resident of Jersey City, Hudson county, New Jersey, and EDWARD AMBROSE, a resident of Troy, Rensselaer county, New York, citizens of the United States, have invented a Design for a Radiator, of which the following is a specification.

Our design is illustrated in the accompanying drawings in which—

Figure 1 represents a radiator made up of a number of sections with our design, and Fig. 2 is a vertical section on the line 1—2, Fig. 1.

The drawings show each radiator section as of the two loop style, each loop being of substantially flattened oval section. The top of each section is slightly widened in outline as at A (Fig. 1), and has ornamental ears a. The top outline a' between the ears is curved as shown. Upon the curved faces of the radiator section are conventional foliated designs in low relief of a somewhat Byzantine type. At the top of each loop at each side the foliation takes a substantially circular form at B, extending over the curved face of the loop. From this circular pattern there extends down each leg of the loop intertwined foliated designs B' in low relief, the foliation diminishing in quantity until it meets and

intertwines with foliation of a similar character extending up from the bottom of the loop.

We are aware that in radiator designs, a circular ornament has been heretofore provided at the top of the loop, but as far as we are aware such circular ornament has always projected out from the loop and had a flat face, like the projection P at the bottom of the loop in Fig. 1, whereas a characteristic feature of our design is that the circular ornament B has a curved face corresponding with the curve formed by the oval section of the radiator loop (Fig. 2).

We claim—

The herein described design for a radiator, as illustrated in the accompanying drawings.

In testimony whereof we have signed our names to this specification in the presence of two subscribing witnesses.

THOS. H. WILLIAMS.
EDWARD AMBROSE.
